(57) **CLAIM**

The ornamental design for a handle/pedal for an actuator, as shown.

DESCRIPTION

FIG. 1 is an upper front right view of a handle/pedal for an actuator in accordance with the present design;

FIG. 2 is a top view of the handle/pedal for an actuator shown in FIG. 1;

FIG. 3 is a bottom view of the handle/pedal for an actuator shown in FIG. 1;

FIG. 4 is a front view of the handle/pedal for an actuator shown in FIG. 1;

FIG. 5 is a rear view of the handle/pedal for an actuator shown in FIG. 1;

FIG. 6 is a left side view of the handle/pedal for an actuator shown in FIG. 1; and,

FIG. 7 is a right side view of the handle/pedal for an actuator shown in FIG. 1.

1 Claim, 3 Drawing Sheets
